(57) **CLAIM**

The ornamental design for a pattern for a flat-surfaced three-dimensional appearing plastic matrix surfacing material, as shown and described.

DESCRIPTION

The file of this patent contains at least one photograph executed in color. Copies of this patent with a color photograph will be provided by the Patent and Trademark Office upon request and payment of the necessary fee.

FIG. 1 is a top plan view of a first embodiment of a flat-surfaced three-dimensional appearing plastic matrix surfacing material showing my new design;

FIG. 2 is a top plan view of a second embodiment thereof; and,

FIG. 3 is a top plan view of a third embodiment thereof.
